Primary Examiner — Robin V Webster

(57) **CLAIM**

The ornamental design for a fan nozzle with directional blades, as shown and described.

DESCRIPTION

FIG. 1 is a top view of the bottom part of a curved fan nozzle with directional blades showing my new design;

FIG. 2 is a front view of the bottom part thereof;
FIG. 3 is a left side view of the bottom part thereof;
FIG. 4 is a front, top perspective view of the bottom part thereof;

FIG. 5 is a bottom view of the top part of a curved fan nozzle with directional blades showing my new design;
FIG. 6 is a front view of the top part thereof;
FIG. 7 is a left side view of the top part thereof;
FIG. 8 is a front, bottom perspective view of the top part thereof;

FIG. 9 is a front, top perspective view of the top part thereof;
FIG. 10 is a top view of the top part thereof;
FIG. 11 is a front view of the top and bottom parts in exploded view;

FIG. 12 is a front view of the top and bottom parts assembled;
FIG. 13 is a top perspective view of the top and bottom parts in exploded view;

FIG. 14 is a top perspective view of the top and bottom parts assembled;

FIG. 15 is a left side view of the top and bottom parts in exploded view;

FIG. 16 is a top side view of the top and bottom parts assembled;

FIG. 17 is a bottom perspective view of the top and bottom parts in exploded view;

FIG. 18 is a bottom perspective view of the top and bottom parts assembled;

FIG. 19 is a top view of the top and bottom parts assembled;

FIG. 20 is a longitudinal cut view of the top and bottom parts assembled; and,

FIG. 21 is a transversal cut view of the top and bottom parts assembled.

The broken lines which define the boundaries of the claimed design form no part of the claimed design. The arrows which define the direction of the top part being attached to the bottom part of the nozzle form no part of the claimed design.
